UNITED STATES PATENT OFFICE.

JOB C. DAVIS, OF SAN FRANCISCO, CALIFORNIA.

QUARTZ-MILL.

Specification of Letters Patent No. 29,470, dated August 7, 1860.

To all whom it may concern:

Be it known that I, Job C. DAVIS, of the city and county of San Francisco and State of California, have invented a new and useful Apparatus for Grinding or Pulverizing Metallic Ores or Tailings, which I call "Davis's Quartz-Mill;" and I do hereby declare that the following is a full, clear, and exact description of the construction and 10 operation of the same, reference being had to the annexed drawings, making a part of this specification, in which—

Figure 1, represents a vertical section of the apparatus; Fig. 2, is a cross section, 15 showing the bed plate; Fig. 3, is a spider-frame; Fig. 4, is the face of one of the grinders; Fig. 5, is a side view of one of the grinders.

A, is an annular trough, similar to that of 20 a common arastrum.

B, B, is a frame to support the shafting.

C, is a circular plate of iron or stone, slightly raised above the bottom of the trough.

D, is a spider-frame, the arms of which 25 are perforated with holes at graduated distances from its center so that said holes in which the grinders E, E, are fastened by means of their rods or shanks, form a spiral 30 line or parallel spiral lines, as represented in Fig. 3.

E, E, are grinders of iron or stone, and are fastened to the under side of the spider-frame by rods passing through the holes 35 above mentioned.

F, is a shaft passing through both spider-frame and bed plate C, the lower end resting on an adjustable bearer K, which bearer passes through the bridge G, and is kept in 40 its proper place by the lever I.

H, is a small annular hopper, and revolves with the spider-frame, from this hopper a pipe or pipes lead directly in front of one or more of the arms of the spider frame.

Mode of operation.—The apparatus being 45 set in motion the crushed ore or tailings, are allowed to run into the hopper H, thence by the pipe or pipes to the bed-plate C, immediately in front of the first or innermost set of grinders, the grinders being rounded on 50 their front edge (as shown in Fig. 5) pass easily on the crushed ore, or tailings, without throwing it suddenly from them, and being placed at an angle with the radii of the spider-frame, the tendency is to slowly 55 throw the ore or tailings toward the trough A; the first set of grinders having passed over the quartz, the second set placed a little farther from the center takes their place, and so on, until the ore or tailings have been 60 subjected to the action of all the grinders.

This method of grinding ores allows of a much greater speed, than is practicable in any other mode of working ores, and is one of its greatest advantages over other 65 methods.

The spider may be divided into any required number of arms, and the grinders into as many sets as desired.

Having described my invention, what I 70 claim therein as new, and desire to secure by Letters Patent, is—

Arranging a series of grinders E so as to form a spiral line or spiral lines around the center shaft, constructed in the manner and 75 for the purposes set forth.

JOB C. DAVIS.
